Oliv. Swift

The schedule referred to in this Letter Patent and making part of the same containing a description in the words of the device. Oliv. Swift having off his improvement in the manner of straightening the toggle joints in the hand printing press. To all persons to whom these presents shall come. Oliv. Swift of Boston in the County of Suffolk and State of Massachusetts a Mechanic and Sonder's greeting. Be it known that I the said Oliv. Swift have invented constructed made and applied to use new and useful improvements in the manner of forming up or straightening the toggle joints in the hand printing press. Which improvements are described in the following words and accompanied drawings which taken together form my specification. First. I attach to the back of the end of the press by screws or otherwise any arm B of the form represented in the drawing or it may be made in any other convenient shape as the fancy or taste of the workman may direct. To this I connect a link C which turns on a pin or bolt a passing through the link arm end of the arm B. In the other extremity of this link I place one end of a bent lever or handle D which extends or turns to the right or left on a pin passing through it and the link as is shown at d. At a point E in this lever or bar C of iron or other metal forked or split open so as to admit the lever to pass through it is concealed by a similar circular pin or bolt to that, as above described. The opposite extremity of this bar moving on a pin or bolt between two end projections on either side of the end of the press towards the operator. Is the pin or bolt one end being bent out in a semicircular form and resting against the bolt or pin at the other having a ball turned on it to fit in a socket in the

lower toggle B, when the lever is pulled by the person, the end of the bar C is carried upwards towards the arch and serves as a moving fulcrum for the lever. The end of the lever to which this piston is attached being kept in a curve differing but very little from a right line during its motion by its connection with the link. The piston is driven forward nearly in straight direction and throughout its full act without much variation perpendicular to the toggles. Secondly the arm B, the link C, the piston D and the toggles E, form, no 2, remaining in precisely the same position with respect to each other as aforesaid. I place a part D of the lever between two ears or projections H, on the inside of the arch, and secure it by a pin or bolt A, on which it is allowed to turn. In the end of the lever I fix a roller G, which acts on a plane or curved surface formed on the side of the link. By pulling the lever the friction roller pushes forward the link which communicates its motion to the piston which resting against the toggles thus straightens the joints. What I claim as my invention and what I consider as new, is the application of the bar C, to the other parts of the combination to produce the effect of straightening the toggle joints in the hand printing press. Also I claim the fixing of a roller in the end of the lever to act against a plane or curved surface on the side of a link C, moving in a curve A, for the purposes aforesaid. The odd lines in both drawings represent the positions of the different parts when the press is not in use and are designated by red letters which correspond with those in black. In testifying, that the above is a true specification of my invention, I have sworn, affixing my hand and seal this 8th day of July, in the year of our Lord eighteen hundred and forty-one.

Witness, Robert H. Estey
